UNITED STATES PATENT OFFICE.

FREDERIC SHIELDS KOCHENDORFER, OF RIVER FOREST, ILLINOIS, ASSIGNOR TO WESTERN ELECTRIC COMPANY, INCORPORATED, OF NEW YORK, N. Y., A CORPORATION OF NEW YORK.

MATERIAL CARRIER FOR STRAND-WRAPPING MACHINES.

Application filed August 31, 1922. Serial No. 585,558.

To all whom it may concern:

Be it known that I, FREDERIC SHIELDS KOCHENDORFER, a citizen of the United States, residing at River Forest, in the county of Cook and State of Illinois, have invented certain new and useful Improvements in Material Carriers for Strand-Wrapping Machines, of which the following is a full, clear, concise, and exact description.

This invention relates to improvements in material carriers for strand wrapping machines.

An object of the invention is to provide a carrier attachable to the serving head of a strand wrapping machine, which may be stacked to form, with others, a magazine, and designed to be readily removable from the machine when the material on the carrier is exhausted.

Another object is to so design the carrier that the amount of material thereon may be observed while the carrier and serving head are in operation.

A further object of the invention is to provide such a carrier with means for retaining thereon a metallic tape in pad form, the retaining means being of such character that the tape is prevented from uncoiling when the pad is in the magazine.

A still further object is to provide a carrier which is simple, durable, and cheap to manufacture.

Other objects and advantages of the invention will be described in detail in the following description and particularly pointed out in the appended claims.

In the accompanying drawings which illustrate one embodiment of the invention.

Fig. 1 is a front elevation of a carrier made in accordance with the invention;

Fig. 2 is a side elevation thereof.

The material carrier herein disclosed is particularly designed for use with the metallic taping machine disclosed in co-pending application Serial No. 585,562, filed

August 31, 1922, but it is to be understood that the carrier may be modified to support various kinds and sizes of wrapping material and to be attachable to different types of strand wrapping machines, without departing from the spirit and scope of the invention.

The carrier comprises a thin, circular, me-

tallic plate 5 having a central opening 6 55 which is flanged over at right angles to the plate to form a narrow hub portion 7 which is designed to fit upon a suitable rotatable support of the taping head. The hub 7 of the carrier is provided with a slot 18 constituting a key-way to receive a suitable key carried by the rotatable support, whereby the said support and carrier are rotatable together. The width of the hub 7 is made slightly greater than the width of the tape 8 supported on the carrier so that the overall width of the carrier is only slightly greater than the width of the tape whereby a relatively large number of the carriers may be stacked and yet form a relatively short magazine. One end 9 of the tape 8 is threaded through spaced parallel slots 10 cut in the hub 7 which provide a means for retaining this end of the tape in place. The tape is coiled on edge to form a pad which rests against the plate 5.

When the tape 8 is made of paper, cloth, or the like, the outer end of the tape may be glued, sewed or otherwise attached to the surface of the adjacent layer of the tape. When the tape is made of metal, a satisfactory means for holding the outer end thereof and preventing the tape from uncoiling comprises a spring 12 having an eye 13 formed on one end thereof, the end 11 of the tape being passed through the eye 13 and bent back upon itself at the point 14. The spring 12 is stretched to place tension on the tape and its other end 15 threaded through a hole 16 made in the plate 5 and bent back upon itself to secure it in place.

The carrier is attached to the taping machine so that the tape is positioned behind the plate 5. In order that the amount of tape on the carrier may be observed during the operation of the taping head, a plurality of large openings 17 are provided in the plate 5 through which the tape may be viewed.

After the tape on the carrier is exhausted, it is desirable that the carrier should be removed from the machine. To remove the carrier, it is first detached from the taping head and then slid over the taped conductor, the conductor passing through the slot 18 which communicates with one of the openings 17, and then through an opening afforded by flexing apart the abutting ends

of the plate formed by a cut 19 which intersects the opening 16.

What is claimed is:

1. A material carrier for strand wrapping machines, comprising a body portion attachable to and removable from the serving head of the wrapping machine and said body portion being provided with a slit, the ends of which are adapted to be flexed apart to form an opening whereby the carrier may be slipped over the wrapped strand to remove it from the machine.
2. A material carrier for strand wrapping machines, comprising a body portion attachable to and removable from the serving head of the wrapping machine, said body portion having openings through which the amount of material on the carrier may be observed while the carrier and serving head are in operation, and said body portion slit whereby the carrier may be slipped over the wrapped strand to remove it from the machine.
3. A carrier for tape in pad form comprising a plate against which the tape pad is disposed, said plate having a hub and slots through which the inner end of the tape may be threaded.
4. A carrier for tape in pad form comprising a plate against which the tape pad is disposed, said plate having a hub and means to which the inner end of the tape may be attached and tension means attached to the plate and to the outer end of the tape to prevent the tape from uncoiling.
5. A carrier for tape in pad form comprising a plate against which the tape pad is disposed, said plate having a hub and means to which the inner end of the tape may be attached and a spring attached at one end to the plate and at its other end to the outer end of the tape to prevent the tape from uncoiling.
6. A carrier for tape in pad form comprising a plate against which the tape pad is disposed, a hub on said plate provided with slots through which the inner end of the tape may be threaded, and a spring attached at one end to the plate and at its other end to the outer end of the tape to prevent the tape from uncoiling.
7. A material carrier for strand wrapping machines, comprising a body portion for supporting the material, said body portion consisting of a plate, against which the material is disposed, and a hub formed on said plate, on which the material is wound, said plate having an opening through which the amount of material on the carrier may be observed while the carrier and serving head of the wrapping machines are in operation.
8. A material carrier for strand wrapping machines comprising a body portion attachable to and removable from the serv-
- ing head of the wrapping machine, said body portion comprising a plate, against which the material is disposed, and a hub, formed on said plate, on which the material is wound, said plate having openings through which the amount of material on the carrier may be observed while the carrier and serving head are in operation.
9. A carrier for tape in pad form comprising a plate against which the tape pad is disposed, said plate being provided with an opening through which the amount of the tape on the carrier may be observed, a hub on said plate, provided with slots through which the inner end of the tape may be threaded, and a spring attached at one end to the plate and at its other end to the outer end of the tape to prevent the tape from uncoiling.
10. A material carrier for strand wrapping machines, comprising a body portion attachable to and removable from the serving head of the wrapping machine, said body portion comprising a plate against which the material is disposed, a hub on said plate provided with slots through which the inner end of the material may be threaded, and a spring attached at one end to the plate and at its other end to the outer end of the material to prevent the material from uncoiling, said body portion slit whereby the carrier may be slipped over the wrapped strand to remove it from the machine.
11. A carrier for strand wrapping machines, comprising a body portion attachable to and removable from the serving head of the wrapping machine, said body portion comprising a plate against which the tape pad is disposed, said plate being provided with an opening through which the amount of the tape on the carrier may be observed while the carrier and serving head are in operation, a hub on said plate provided with slots through which the inner end of the tape may be threaded and a spring attached at one end to the plate and at its other end to the outer end of the tape to prevent the tape from uncoiling, said body portion slit whereby the carrier may be slipped over the wrapped strand to remove it from the machine.
12. A carrier for strand material comprising a body portion against which the material may be disposed, said body portion having openings through which the inner end of the strand material may be threaded.
13. A carrier for strand material comprising a body portion against which the material may be disposed and means attachable to the body portion and to the strand material to prevent the said strand material from uncoiling.
14. A carrier for strand material comprising a body portion against which the material may be disposed, said body portion

having means to which the inner end of the material may be attached and means attachable to the body portion and to the strand material to prevent the said strand material 5 from uncoiling.

15. A carrier for strand material comprising a body portion against which the material may be disposed, said body portion having means to which the inner end of the 10 material may be attached and elastic means attached to the body portion and to the strand material to prevent the said strand material from uncoiling.

16. A material carrier for strand wrapping machines, comprising a body portion 15 for supporting the material and an element carried by said body portion on which the material is wound, means attachable to the body portion and to the strand material to 20 prevent the said strand material from uncoiling, said body portion so designed that

the carrier may be slipped over the wrapped strand to remove it from the machine.

17. A carrier for strand material comprising a body portion against which the 25 material may be disposed, said body portion having means to which the inner end of the strand material may be attached.

18. A material carrier for strand wrapping machines, comprising a body portion 30 for supporting the material and an element carried by said body portion on which the material is wound, said body portion having means to which the inner end of the material may be attached and means attachable 35 to the body portion and to the strand material to prevent the said strand material from uncoiling.

In witness whereof, I hereunto subscribe my name this 26th day of August A. D., 40 1922.

FREDERIC SHIELDS KOCHENDORFER.
